STITCH-FORMING MACHINE

Max Bretschneider, Plauen, Germany

Application October 29, 1930, Serial No. 492,042
In Germany November 4, 1929

11 Claims. (Cl. 112—95)

The present invention relates to an improvement in stitch-forming machines.

The increase of working speed in embroidering machines of the multi-needle type as well as in sewing machines requires the substitution of circular for longitudinal shuttles to exclude mass action as much as possible, it being necessary, however, to make provision for slackening the thread during frame adjustments. For this purpose, according to the invention, the holder keeping the shuttle within reach of the looper, is arranged rotatably, a feature of importance not only to multi-needle embroidering machines but also to single-needle sewing machines and capable of widest application. In order to arrange in multi-needle machines a plurality of circular shuttles closely side by side in accordance with the repeat of the embroidering machine and rotate their loopers from a common driving shaft, the looper shafts are disposed vertically, each of them being rotated from the driving shaft by means of a helical gear drive. The holder of the shuttles is positioned vertically displaceable relative to the machine frame, but held by a crank device adapted to reciprocate the holder and the shuttles for the purpose of delivering the thread during the motion of the frame. The driving shaft of the shuttles rotates irregularly in the manner known in sewing machine construction, and this irregular rotation is attained in a special way according to the invention. To introduce the breadths of fabric without any trouble, the invention disposes the shuttle carriage preferably vertically displaceable relative to the machine frame so that the frame struts need not be removed when the fabric is changed and can serve as supports for the frame.

One embodiment of the invention is illustrated in the accompanying drawings, in which Figure 1 is a side view and section of the shuttle carriage guide, the bearings of the circular shuttles and the drive of the loopers; Fig. 2, a view of the shuttle carriage as seen from the operating side thereof. Fig. 3, a view from below of the crank device for producing rotation of the shuttles to give thread; Fig. 4, an end view of the machine frame and of the transmission of motion from the main shaft of an embroidering machine to the shuttle driving shaft; Fig. 5, a front view of Fig. 4 seen in the direction of the arrow A in Fig. 4; Figs. 6 to 8 are, respectively, a side view, a plan and an axial section of the coupling of the looper driving shaft with the shaft end positioned on the machine frame and rotated by the main shaft; Fig. 9 is an end view of an embroidering

machine disclosing the suspension and mutual balancing of two oppositely arranged shuttle carriages; Fig. 10, a rear view of the suspension of the shuttle carriages seen from the needle side in the direction of the arrow B in Fig. 9; Fig. 11, a view of arranging a shuttle between the looper and holder; Fig. 12, a section of the shuttle; Fig. 13, a plan thereof; Fig. 14, a view of a jointed shaft; Fig. 15, a view of a sewing machine; and Fig. 16 is a view on a larger scale of the details of the machine of Fig. 4.

Referring to the drawings, the circular shuttles 1 are essentially of the same shape as those in sewing machines, but provided with a cover 2 so that the bobbins 100 may be inserted and kept out of touch with the looper 15. The use of bobbins insures uniform and easy take-up regardless of the thread reserve, the thread being guided away from the inner windings of the bobbin through a hole 101 in the center of the cover 20 and in a depressed portion 104 on the outside of the latter over the outer edge of the shuttle 1 under the tension spring 102, the perforations 103 in the side wall of the shuttle permitting convenient inspection of the thread reserve. The shuttle 20 rests on a portion of the bevelled upper edge of the holder 3, and the part on both sides of the notch 106 to be engaged by the finger 105 does not slope for a short distance, the finger 105 serving to prevent the looper 15 from driving the shuttle. 30

Each holder 3 is displaceably positioned by means of the bolt 4 in the bushing 5 of the shuttle carriage 6 and is pressed upwardly by the spring 7, while the crank 8 secured to the lower end of each bolt 4 is adjacent the lower side of the shuttle carriage 6 and limits the upward motion of the bolt 4.

The cranks 8 are connected by pins 9 with a common draw bar 10 disposed parallel to the shuttle carriage 6 and reciprocated at one end by hand or by the machine. The draw bar 10 carrying out one reciprocatory motion during each rotation of the shaft 20 to move the shuttles 1 to deliver a length of thread from the bobbin. 40

If a shuttle is to be removed, the bolt 4 is drawn down by means of the head 11, whereby the holder 3 with the shuttle, which is loosely disposed therein, is lowered. Each shuttle can operate independently of the others when its thread for any reason becomes slack and only a short length has to be drawn out, for which purpose the corresponding crank 8 is disconnected from the bar 10 and rotated. 45

By means of the holders 3 the shuttles 1 are kept within range of the loopers 15 above them 50

without, however, touching them. Each looper 15 is carried by a shaft 16 rotatably arranged about a vertical axis in the bushing 17 of the looper carriage 6. To the upper end of the shaft 16 a helical gear 18 is secured engaging a corresponding helical gear 19 on the shaft 20 which carries as many helical gears 19 as there are needles or shuttles on one machine side. During the rotation of the shaft 20 the loopers 15 are turned, each looper thus gripping the thread fed by the respective needle and forms it into a loop as in known sewing machines. Towards the needle side the shuttle carriage is covered by the needle plate 21 to prevent the fabric from coming within range of the loopers.

The working method of the loopers requires irregular rotation of the latter, which can be attained in various ways; for example, by rotating the driving shaft 22 by means of untrue gears. According to the invention, driving power is transmitted from the main shaft 22 of the machine (Fig. 4) to the shaft member 200 detachably connected with the looper driving shaft 20 in the following manner:

The main shaft 22 carries an eccentric 23. The eccentric ring or strap 24 carries an arm 25 provided with a guide channel 26 engaged by the sliding block 27 which is rotatably disposed on the bolt 28 held in position by the machine frame so that the motion of the arm 25 determined by the bolt 28 and the eccentric 23 takes place during the operation of the eccentric. A slot 30 is formed in the free end of the arm 25 extending transversely to the latter and a pin 29 is adjustably arranged in the slot. This pin 29 is engaged by the guide rod 31, the other end of which is articulated relative to the pin 32 of a crank 33 secured to the shaft member 200. The pin 29 moves in an orbital path at an irregular speed and, by means of the guide rod 31, causes the crank pin 32 and the shaft 200 on which it is mounted to move with a correspondingly irregular motion as the shaft 200 is coupled with the shaft 20, which motion is transmitted by the helical gears 18 to the loopers 15.

To displace the shuttle carriage 6 in upward direction so as to facilitate the insertion of the embroidering fabric wound on a roll between the carriage 6 and the needle carrying rods 35, the carriage 6 can be displaced vertically along the guide rod 39 by means of the sleeves 36 and 37, the rod 39 being secured to the machine frame. As good balancing of the masses of the horizontally reciprocating needles and their driving parts makes it necessary to dispose the embroidering tools in two opposite rows and to cause the tools and parts to move in opposite directions, the two carriages may be easily balanced and, for this purpose, are suspended by means of the holding rods 40 from double-armed levers 41 rotatably disposed on the upper end of the machine frame by means of the bolts 42; furthermore, all of the sleeves 36 for one of the two shuttle carriages of the embroidering machine are connected with the racks 50 which are engaged by the pinions 51 positioned on the shaft 52 which can be rotated by the double-armed adjusting lever 53 so that the shuttle carriage 6 can always be moved up on the machine side where the fabric is to be exchanged to facilitate the introduction of the cloth rollers. In working position the shuttle carriages 6 are held by the levers 55 on the shaft 56, which can be adjusted underneath the horizontal arms 58 of the carriages 6 by means of their carrier rolls 57, the general arrangement

being so as to move the supporting levers 55 at a small angle beyond the dead center position to support the shuttle carriages and lift the latter sufficiently to relieve the holding rods 40 so that the weight of the carriages rests exclusively on the levers 55 and any vibration of the carriages is eliminated.

To avoid the necessity of separating the gear for transmitting driving motion from the main shaft 22 to the driving shaft 20 at a vertical displacement of the shuttle carriage 6, the shaft 20 is divided according to Figs. 5 to 8 in the manner suggested above. The shaft members 20 and 200 are thus connected by the coupling members 44, 45, and 46, the intermediate member 45 being 15 connected to the adjacent members 44 and 46 by key and groove positioned vertically to the axis of the shaft while the keying between the members 44 and 45 is disposed vertically to that between the members 45 and 46. In this way the 20 intermediate member 45 is held reliably between the other two members in any position and transmission of motion from one shaft member to the other insured even if, owing to inaccurate adjustment of the carriage 6, the axes of the two shaft 25 members are not exactly aligned. To prevent the intermediate member 45 from dropping off from the coupling member 44 after an adjustment of the shuttle carriages and a separation of the shaft members 20 and 200, it is held in position 30 relative to the coupling member by the pin 47 secured to the member 45 and projecting loosely through a cross bore of the shaft 200. The connection of the shaft members 20 and 200 may be carried out in different ways, and instead of separating them from one another at a displacement of the shuttle carriages, their effective connection may be retained by the interposition of an extensible jointed shaft comprising, according to Fig. 14, two parts 201 and 202 adapted to be 40 telescoped and connected in any suitable manner, such as, for example, by key and groove or slot and cross pin, so that torques are reliably transmitted from one part to the other. The parts are connected by Cardan joints and the like to the 45 shaft members 20 and 200 so that during an upward motion of the shaft 20 its connection with the shaft 200 is not interrupted.

As the space below the loopers is occupied by the holder 3 and its parts, the bore tools must be 50 arranged between the shuttles, an arrangement which affords the considerable advantage that the fabric on both sides of the bore tools is held in position by the presser members whereby the otherwise unavoidable noise is eliminated, which is 55 of special importance particularly in high speed machines.

The arrangement described may be varied in many ways and adapted to all sorts of conditions. In particular, the drive described for attaining a 60 reciprocating motion of the shuttle can be used profitably also in one-needle sewing machines in order to provide for better thread giving than was possible till now.

Fig. 15 shows the application of the invention 65 to a sewing machine, the essential parts of which are known. Above the table 320 the standard 321 with the arm 322 and the head 323 is arranged, the needle carrying rod or bar 324 being capable of moving up and down in the head 323 70 and is driven by the main shaft 325. The needle bar 324 carries the needles 326 within range of which the looper 315 is disposed under the table 320 and held by the shaft 316 rotatably positioned in the brackets 327 and 328. The free 75

end of the shaft 316 carries a crank 329 which is rotated in the known manner from the main machine shaft 325. As this kind of gear is known, it is indicated only in the drawings by the dotted line 330.

Within range of the looper 315 the shuttle 301 is found which is held by the holder 303 carried by the shaft 305 positioned in a side arm 331 of the bracket 328. The free end of the shaft 305 carries a crank 332 which, by means of the rod 333, can be moved to and fro from a crank 334 secured to a shaft 335 rotatably arranged in the brackets 327 and 329. The other end of the shaft 335 carries also a crank 336 which can be moved to and fro from the main shaft 325 by means of the rod 337. For this purpose the main shaft 325 is provided with a cam 338 which causes the rod 337 to be moved up and down.

I claim:—

20. 1. In a stitch-forming machine, the combination of a plurality of needles, a looper disposed within range of each needle and rotatably disposed relative to the machine frame, the axes of the loopers being disposed transversely to the needles, a toothed wheel for each looper adapted to be driven by another toothed wheel, an auxiliary shaft, gears on the said shaft and adapted to drive the loopers, a crank, a crank pin, a guide rod secured to one end of the said auxiliary shaft and adapted to engage with one end of the said crank pin, a main driving shaft disposed parallel to the said auxiliary shaft, an eccentric arranged on the said main shaft, an eccentric rod driven by the eccentric, a guide channel on the said eccentric rod, a block adapted to slide in the guide channel, a bolt connecting the block to the machine frame, means for connecting the free end of the said eccentric rod with the said guide rod, the said means being adjustable transversely to the longitudinal direction of the said eccentric rod, a circular shuttle positioned under each looper, and a holder for each shuttle, the said holder being arranged under each shuttle and adapted to carry the shuttle, the said loopers and shuttles being separated by an intermediate space.
25. 2. In a stitch-forming machine, the combination of a plurality of needles, a looper disposed within range of each needle and rotatably disposed relative to the machine frame, the axes of the loopers being disposed transversely to the needles, a pinion for each looper adapted to be driven by another pinion, an auxiliary shaft provided with gears for driving the loopers and arranged on the shuttle guide adapted to be moved up and down on the machine frame, coupling members secured to one end of the auxiliary shaft, a second shaft connected with the first shaft by the said coupling members and arranged on the machine frame, a crank connected with the free end of the said second shaft, a crank pin, a guide rod secured to one end of the said auxiliary shaft and adapted to engage with one end of the said crank pin, a main driving shaft disposed parallel to the said auxiliary shaft, an eccentric arranged on the said main shaft, an eccentric rod driven by the eccentric, a guide channel on the said eccentric rod, a block adapted to slide in the guide channel, a bolt connecting the block to the machine frame, means for connecting the free end of the said eccentric rod with the said guide rod, the said means being adjustable transversely to the longitudinal direction of the said eccentric rod, a circular shuttle positioned under each looper, and a holder for each shuttle, the said holder being arranged under each shuttle and adapted to carry the shuttle, the said loopers and shuttles being separated by an intermediate space.
30. 3. In a stitch-forming machine, the combination of a plurality of needles, a looper disposed within range of each needle and rotatably disposed relative to the machine frame, the axes of the loopers being disposed transversely to the needles, a toothed wheel for each looper adapted to be driven by another toothed wheel, an auxiliary shaft, gears on the said shaft and adapted to drive the loopers, a crank, a crank pin, a guide rod secured to one end of the said auxiliary shaft and adapted to engage with one end of the said crank pin, a main driving shaft disposed parallel to the said auxiliary shaft, an eccentric arranged on the said main shaft, an eccentric rod driven by the eccentric, a guide channel on the said eccentric rod, a block adapted to slide in the guide channel, a bolt connecting the block to the machine frame, means for connecting the free end of the said eccentric rod with the said guide rod, the said means being adjustable transversely to the longitudinal direction of the said eccentric rod, a circular shuttle positioned under each looper, and a holder for each shuttle, the said holder being arranged under each shuttle and adapted to carry the shuttle, the said loopers and shuttles being separated by an intermediate space.
35. 4. In a stitch-forming machine, the combination of a reciprocating needle, a looper adapted to cooperate with the said needle, a circular shuttle arranged within range of the said looper, a perforated and grooved cover for the said circular shuttle, the perforation being in the center of the cover and the groove extending from the perforation to the edge, a holder adapted to hold the shuttle during the motion of the said looper, and means rotatably arranged in the machine frame and adapted to turn the said holder.
40. 5. In a stitch-forming machine, the combination of a machine frame, a series of reciprocating needles, a rod disposed on each side of the said frame, means for moving the two rods oppositely to one another, loopers reciprocated by said rods and rotatably carried by vertical axes, said loopers being adapted to cooperate with the needles, a plurality of circular shuttles, one shuttle each being arranged under each looper, holders rotatably disposed with vertical axes under the shuttles and adapted to carry them, double levers positioned in the upper portion of the machine frame, and connecting rods on the free ends of the double levers adapted to connect said ends with the two rods.
45. 6. A stitch-forming mechanism, comprising a needle, a looper rotatably arranged in the machine frame and adapted to cooperate with the said needle, a circular shuttle arranged within range of the said looper, a carrier adapted to carry the shuttle, and means to rotate said shuttle carrier together with said shuttle around its 75

for each shuttle, the said holder being arranged under each shuttle and adapted to carry the shuttle, the said loopers and shuttles being separated by an intermediate space.

3. In a stitch-forming machine, the combination of a plurality of needles, a looper disposed within range of each needle and rotatably disposed relative to the machine frame, the axes of the loopers being arranged transversely to the needles, a pinion for each looper adapted to be driven by another pinion, an auxiliary shaft provided with gears for driving the loopers and arranged on the shuttle guide adapted to be moved up and down on the machine frame, coupling members secured to one end of the auxiliary shaft, a second shaft connected with the first shaft by the said coupling members and arranged on the machine frame, the said coupling members comprising three discs interconnected by key and groove directed transversely to the axis of the shaft, the disc connected with the auxiliary shaft being upwardly displaceable away from the middle disc, a crank connected with the free end of the said second shaft, a crank pin, a guide rod secured to one end of the said auxiliary shaft and adapted to engage with one end of the said crank pin, a main driving shaft disposed parallel to the said auxiliary shaft, an eccentric arranged on the said main shaft, an eccentric rod driven by the eccentric, a guide channel on the said eccentric rod, a block adapted to slide in the guide channel, a bolt connecting the block to the machine frame, means for connecting the free end of the said eccentric rod with the said guide rod, the said means being adjustable transversely to the longitudinal direction of the said eccentric rod, a circular shuttle positioned under each looper, and a holder for each shuttle, the said holder being arranged under each shuttle and adapted to carry the shuttle, the said loopers and shuttles being separated by an intermediate space.

4. In a stitch-forming machine, the combination of a reciprocating needle, a looper adapted to cooperate with the said needle, a circular shuttle arranged within range of the said looper, a perforated and grooved cover for the said circular shuttle, the perforation being in the center of the cover and the groove extending from the perforation to the edge, a holder adapted to hold the shuttle during the motion of the said looper, and means rotatably arranged in the machine frame and adapted to turn the said holder.

5. In a stitch-forming machine, the combination of a machine frame, a series of reciprocating needles, a rod disposed on each side of the said frame, means for moving the two rods oppositely to one another, loopers reciprocated by said rods and rotatably carried by vertical axes, said loopers being adapted to cooperate with the needles, a plurality of circular shuttles, one shuttle each being arranged under each looper, holders rotatably disposed with vertical axes under the shuttles and adapted to carry them, double levers positioned in the upper portion of the machine frame, and connecting rods on the free ends of the double levers adapted to connect said ends with the two rods.

6. A stitch-forming mechanism, comprising a needle, a looper rotatably arranged in the machine frame and adapted to cooperate with the said needle, a circular shuttle arranged within range of the said looper, a carrier adapted to carry the shuttle, and means to rotate said shuttle carrier together with said shuttle around its 75

own axis during the motion of said looper, but independently from the looper.

7. In a stitch-forming mechanism the combination of a plurality of needles horizontally arranged, a looper disposed within range of each needle and above the level of said needles adapted to cooperate therewith, the axis of the said looper being disposed vertically, a circular shuttle arranged under each looper and being separated therefrom by an intermediate free space, and a carrier or supporter for each shuttle positioned under the shuttle and adapted to carry the shuttle independently from said looper.

8. A mechanism according to claim 6, in which members are provided adapted to connect the means for turning the carrier with the needle driving means to automatically move the carrier after a stitch-forming operation and tensioned prior to further operation, and in which means are provided to uncouple the said carrier from said driving means and to rotate said carrier manually.

9. In a stitch-forming machine, the combination of a plurality of needles, a looper disposed within range of each needle and adapted to cooperate with the needle, the axis of the said looper being disposed vertically, a circular shuttle arranged under each looper, and a holder for each shuttle positioned under the shuttle and adapted to carry the shuttle, the said loopers and shuttles being separated by an intermediate space permitting passage of the thread from the shuttle without resistance, and the holder being

vertically adjustable to facilitate the removal and exchange of the shuttles.

10. In a stitch-forming machine, the combination of a plurality of needles, a looper disposed within range of each needle and adapted to cooperate with the needle, the axis of the said looper being disposed vertically, a circular shuttle arranged under each looper, a holder for each shuttle positioned under the shuttle and adapted to carry the shuttle, the said loopers and shuttles being separated by an intermediate space permitting passage of the thread from the shuttle without resistance, a guide carrying the loopers and holders, and means adapted to adjust the said guide vertically relative to the machine frame.

11. In a stitch-forming machine, the combination of a plurality of needles, a looper disposed within range of each needle and adapted to cooperate with the needle, the axis of the said looper being disposed vertically, a circular shuttle arranged under each looper, a holder for each shuttle positioned under the shuttle and adapted to carry the shuttle, the said loopers and shuttles being separated by an intermediate space permitting passage of the thread from the shuttle without resistance, a guide carrying the loopers and holders, means adapted to adjust the said guide vertically relative to the machine frame, and bolts adjustably arranged on the machine frame and adapted to carry the guide with the loopers and holders to relieve the means serving to adjust the guide.

MAX BRETSCHNEIDER.
